Nov. 17, 1931.

F. M. HUNTER

1,832,709

UNDERGARMENT

Filed Jan. 26, 1931

Inventor

Frank M. Hunter
By Langdon Moore

Attorney

UNITED STATES PATENT OFFICE

FRANK M. HUNTER, OF LITITZ, PENNSYLVANIA.

UNDERGARMENT

Application filed January 26, 1931. Serial No. 511,420.

This invention relates to improvements in undergarments, and more especially to a lady's undergarment having an outer facing of genuine silk or rayon for the sake of appearance, but lined with a relatively coarse textile fabric for the purpose of warmth.

The primary object of the invention is to provide an undergarment made of silk or rayon fabric but lined with cotton or cotton 10 and wool fabric or the like; the facing cloth and the lining being so connected as not to detract from the appearance of the garment or to betray the fact that it is lined to provide a warmer garment.

With the foregoing objects outlined and with other objects in view which will appear as the description proceeds, the invention consists in the novel features hereinafter described in detail, illustrated in the accompanying drawings, and more particularly pointed out in the appended claim. I have shown the invention as embodied in bloomers for women, but it is to be understood that the same is adaptable for the making of undergarments for men and children.

In the drawings,

Fig. 1 is a front elevation of the improved undergarment partially broken away for the purpose of illustration.

Fig. 2 is a rear view of the same.

Fig. 3 is a horizontal sectional view of a detail on the line 3—3 of Fig. 1.

Fig. 4 is a vertical sectional view of a detail on the line 4—4 of Fig. 1.

Fig. 5 is a similar view of a detail on the line 5—5 of Fig. 2.

Referring to the drawings, it will be noted that the facing or outer part of the garment is made of two leg portions 6 and 7, and a 10 triangular crotch portion 8, formed of genuine silk or rayon. The lining is formed of like leg portions 9, but preferably made of cotton or cotton and wool fabric or the like, and a crotch portion similar to the 15 crotch portion 8, which may be made of some soft material, such as silk or rayon fabric, or I may employ cotton or cotton and wool fabric, or the like.

At the lines where the facing sections are 20 sewed together, they are also sewed to the lining sections as shown in Fig. 3; the edges of the fabric being turned inwardly and being connected together by stitching 10.

The upper edges of the facing and lining fabrics are folded over as at 11 in Fig. 5, and between these folded over edges, the lower edge of an elastic belt 12 is inserted, and sewed to the facing and lining by stitching 13. However, it will be understood that the elastic belt 12 may be enclosed within the 55 folds of the upper edges of the inner and outer fabrics in the same manner as illustrated in Fig. 4 for securing the elastic band in the ends of the leg portions, now to be described.

The leg opening portions of the facing and lining are turned inwardly and doubled over as indicated at 14 in Fig. 4, and are sewed together by two lines of threads 15. In the annular pocket 16 thus formed, an 70 elastic band 17 is enclosed for the purpose of contracting the leg opening. However it will be understood that the elastic band 17 may be attached to the leg opening portions in the manner illustrated in Fig. 5 for securing the elastic belt 12.

The lining is preferably of the same color as the facing, and this will enhance the general appearance of the garment and tend to conceal the fact that the garment is lined 80 with a warm fabric.

It will be understood that the facing may be of any suitable textile fabric presenting the pleasing appearance desired by the wearer, while the lining may be of any suitable fabric which will be comfortable and increase the warmth of the garment.

From the foregoing it is believed that the construction and advantages of the invention will be readily understood by those skilled in the art, and it is apparent that changes may be made in the details disclosed, without departing from the spirit of the invention, as expressed in the claims.

What I claim and desire to secure by Letters Patent is:

An undergarment formed of leg sections and a crotch section made of silk fabric comprising the facing, and a lining for the undergarment formed of relatively warm soft 100 textile material and made in sections corresponding to the sections of the facing fabric, the facing sections and the lining sections being sewed together along seam lines extending medially from the top portion of the front to the top portion of the rear of the undergarment, the edges of the facing fabric being folded inwardly toward the lining fabric and the edges of the lining fabric being folded inwardly toward the facing fabric along said seam lines, and the folded edge portions of the facing and lining fabrics of adjacent sections being in abutting relation to one another along said seam lines.

15

FRANK M. HUNTER.

20

25

30

35

45

50

55

60

65